UNITED STATES PATENT OFFICE.

WALTER GRAY, OF FORT HUACHUCA, ARIZONA, ASSIGNOR OF ONE-HALF TO HEZIKIH SESSION, OF FORT HUACHUCA, ARIZONA.

EXTENSIBLE STEP.

1,163,529.

Specification of Letters Patent.

Patented Dec. 7, 1915.

Application filed April 28, 1915. Serial No. 24,554.

To all whom it may concern:

Be it known that I, WALTER GRAY, a citizen of the United States, residing at Fort Huachuca, in the county of Cochise and State of Arizona, have invented certain new and useful Improvements in Extensible Steps; and I do hereby declare the following to be a full, clear, and exact description of the invention, such as will enable others skilled in the art to which it appertains to make and use the same.

This invention relates to steps and more particularly to steps of the extensible type especially designed for use in connection with railway passenger cars.

The invention has for its object to provide extensible steps for cars including upper and lower sections, the upper section being movable relative to the lower section, whereby the latter may be elevated when the car is traveling.

Another object is the provision of novel and efficient means for elevating and retaining the relatively movable section in operative position.

With these and other objects in view, the invention consists in the novel construction, arrangement and formation of parts as will be hereinafter specifically described, claimed and illustrated in the accompanying drawing, in which:

Figure 1 represents a rear elevation of the extensible step applied to the platform of a car. Fig. 2 represents a vertical sectional view on the line 2—2 of Fig. 1. Fig. 3 represents a sectional view similar to Fig. 2, illustrating the steps in retracted or inoperative position. Fig. 4 represents a perspective view of the upper or relatively stationary section. Fig. 5 represents a fragmental perspective view of the lower or relatively movable section. Fig. 6 represents a fragmental perspective view of the relatively movable step slidably mounted in the upper section, and Fig. 7 represents a detailed sectional view on the line 7—7 of Fig. 3.

Referring to the drawing in detail, wherein similar reference numerals designate corresponding parts throughout the several views, the numeral 10 indicates generally the upper section of the steps which includes an attaching plate 11 and a pair of spaced inclined side members 12 secured to and depending from the plate 11. A relatively

stationary step 13 is rigidly secured between the side members 12 and is formed in its ends with recesses 14 slidably receiving the upstanding guide members 15 carried by the lower or relatively movable section, designated generally by the numeral 16 and illustrated in detail in Fig. 5. Below the stationary step 13 the side members 12 are formed with longitudinally elongated openings 17 slidably receiving the central longitudinal extensions 18 of a vertically movable step 19. Relatively narrow elongated openings 20 are formed in the lower portions of the side members 12 upon opposite sides of the openings 17 and receive the relatively small extensions or lugs 21 formed on the ends of the movable step 19 for securing the latter against tilting forwardly or rearwardly. The openings 17 and 20 in the side members are of sufficient length to permit the movable step 19 to be moved upwardly into engagement with the relatively stationary step 13, when the steps are moved to inoperative position.

The lower or relatively movable section 16 includes a pair of spaced side members 23 slidably engaged against the inner surfaces of the side members 12 of the upper section 10, and the guides, or supporting brackets, 15 are secured to the side members 23, as clearly illustrated in Fig. 5. The upper extremities of the guides 15 are formed with longitudinally elongated openings 24 receiving the central extensions 18 of the relatively movable step 19, whereby the lower or relatively movable section is supported in extended position. A step 25 is secured between the upper extremities of the side members 23 and is adapted, when the lower section is moved upwardly to inoperative position, to engage and move therewith the relatively movable step 19 of the upper section. As many steps 26 as are required are secured between the side members 23 below the upper step 25.

The upper section 10 is rigidly and permanently secured to the under side of the platform 27 of a railway passenger car. A shaft 28 is rotatably supported below the platform 29 and a winding drum 30 is keyed upon one end of the shaft in vertical alignment with the longitudinal center of the extensible steps. A cable 31 is secured at one end to the drum 30 and at its opposite end to the lowermost step 26 of the lower section 110.

16. An operating lever 32 is pivotally secured in the platform 27 and carries a gear segment 33 at its lower extremity which meshes with a pinion 34 secured to the shaft 28 at the end opposite the drum 30. The upper end of the lever 22 carries a handle, whereby the same may be oscillated to rotate the shaft 28 and drum 30 and thus wind and unwind the cable 31 to raise and lower the extensible section 16. A suitable type of locking mechanism 35 is provided for locking the lever 32 and coöperating parts in adjusted position.

15 In use, the lower section 16 and relatively movable step 19 automatically drop to operative position, when the lever 32 is moved outwardly, by gravity, the section 16 being supported by the guides 15 engaged over the central extensions 18 of the relatively movable step 19. When the lever 32 is moved inwardly to the position illustrated in Fig. 3, the cable 31 is wound upon the drum 30 and the lower section 16 is drawn upwardly thereby, to the position illustrated in Fig. 3, the upper step 25 of the lower section engaging and lifting the relatively movable step 19 of the upper section 10 and moving it into engagement with the step 13.

20 What I claim is:

30 1. An extensible step including a relatively stationary section, a movable section, means for guiding and limiting the movement of the movable section including a step movably secured in the relatively stationary section, and means for elevating the movable section.

35 2. An extensible step including a rela-

tively stationary section, a movable section, a step movably disposed in the relatively stationary section adapted to be engaged and elevated by the movable section.

5 3. An extensible step comprising a relatively stationary section, a movable section, a movable step secured in the relatively stationary section adapted to be engaged and moved upwardly by the movable section, and means for elevating the movable section.

10 4. An extensible step comprising a relatively stationary section, a movable section, a movable step secured in the relatively stationary section adapted to be engaged and elevated by the movable section, a shaft, a lever connected with said shaft, and connections between said shaft and the movable section.

15 5. An extensible car step comprising an upper section, a step movably secured in said upper section, a lower section, and means connecting said lower section with said movable step and movable relative thereto.

20 6. An extensible car step comprising a relatively stationary section, a movable step secured in said section, a movable section, means connecting said movable section with said movable step and movable relative thereto, and means for elevating the movable section.

25 In testimony whereof I affix my signature in presence of two witnesses.

WALTER GRAY.
